THOMAS COFFEY, OF WEST TULSA, OKLAHOMA.

ARCH-SUPPORTING SHOE.

1,272,223.

Specification of Letters Patent.

Patented July 9, 1918.

Application filed November 20, 1917. Serial No. 202,990.

To all whom it may concern:

Be it known that I, THOMAS COFFEY, a citizen of the United States, residing at West Tulsa, in the county of Tulsa and 5 State of Oklahoma, have invented certain new and useful Improvements in Arch-Supporting Shoes, of which the following is a specification.

This invention relates to an arch supporting shoe, and particularly to a shoe of the 10 character described in which arch supporting structure is introduced in the manufacture of the shoe and is so constructed that the individual requirements of each 15 particular wearer may be suited.

An object of the invention is to provide 20 an arch supporting shoe having arch supporting structure embodied therein in such a way that a number of different adjustments can be made to thus obtain the proper support for the foot and arch structure of each individual wearer, and also to make 25 the supporting structure of such character that it will not wear and chafe upon the foot or bruise the same as is sometimes the case where metal and other more or less rigid plates are employed.

Another object is to so construct the parts 30 that the arch of the foot is held by pneumatic and inflatable means, which means will give an air cushion for the bearing of the foot and at the same time allows of a number of different adjustments.

Yet another object lies in constructing 35 parts associated with the pneumatic cushion which provides virtually a cushion insole beneath the heel and ball portions of the foot as well as under the instep.

With the above and other objects in view, 40 which will be in part described and in part understood from the specification, drawings, and claims, my invention consists in certain novel features of construction and combination of parts which will be hereinafter more 45 fully set forth.

In the drawings:—

Figure 1 is a sectional view taken longitudinally through the lower portion of a 50 shoe having my invention embodied therein; and,

Fig. 2 is a view in plan of the inner sole structure with the upper entirely disregarded for better illustration.

The shoe upper 1 may be of usual and

any standard construction as may also the 55 outer sole 2 and the heel 3, and in fact the main parts of the shoe will be substantially standard in all respects as viewed from the outside, except for slight additions which will be hereinafter more fully set forth. 60

A middle sole 4, which is preferably of leather or other material possessing some body or stiffening is shaped to be received within the shoe upon the outer sole structure 2, and the plates 5 and 6 which are 65 hingedly connected together are cemented or otherwise secured on the sole portion 4 at the instep and are so disposed that the hinge pindle extends transversely across beneath the instep. An inner sole 7, which is also 70 of a material having inherent stiffness but yet sufficiently flexible to give and conform somewhat to the motion of the foot within the shoe, is mounted above the middle sole 4 and is held spaced therefrom by springs 75 8, 9, and 10, which are placed between the middle and inner soles at such points that they will be disposed beneath the heel of the foot, beneath the ball, and at the outer side of the arch, substantially as is indicated in 80 Fig. 2.

It is of course to be understood that the inner sole will be permitted movement with respect to the middle sole, and therefore the springs 8, 9, and 10, will mount the inner 85 sole 7 in such a way that it will act as a cushion insole, however, as is stated above it is one of the purposes of this invention to provide for adjustment to various heights of foot arches, and therefore I cut the inner 90 sole material away entirely as indicated at 11, or reduce this inner sole 7 beneath the arch to such an extent that it is very flexible. As has been stated, in the present instance I have shown the inner sole as being cut out 95 beneath the arch as shown at 11, and to give an unbroken surface to the upper side of the inner sole, a lining strip 12 is placed and secured thereover to cover over the opening 11 of the inner sole, it of course being 100 understood that this will give flexibility at this point. An inflatable bladder or bag 13 is mounted on the inner sole 4 over the plates 5 and 6, and is so disposed that it has the upper side thereof received in the opening 11 or in the reduced and flexible portion of the inner sole 7, and this bladder which may be 105 of gum rubber, rubberized fabric, or other

suitable material, has a stem 14 extending therefrom through the middle sole 4 and then through the outer sole 2 close back adjacent the heel 3 so that it will be protected. 5 This stem 14 has a valve structure therein which may be of any desired conception as for instance made in any of the standard and approved ways, and as air is forced in through the stem 14 into the bladder 13, the 10 same will be inflated to raise the inner sole at the instep, it being understood that as greater or lesser inflation is given to the bladder 13 the instep portion of the inner sole will be raised to a greater or lesser 15 height.

The inflatable bladder 13 is intended to raise the inner sole so that proper support will be given to the foot in the metatarsal arch, and it is perhaps preferable that the 20 inflatable bladder structure and the covering therefor be extended somewhat as is shown in Fig. 2 so that a portion of the inflatable structure will lie adjacent the upper of the shoe in the instep portion thereof, 25 thus giving support to the metatarsal arch on the plantar surface and at the sides. Under some circumstances it may be desired to give a greater rise in the instep arch than can be obtained by inflation of the bladder 30 13, or to make the arch support more rigid with only a slight pneumatic cushion thereover, and it is with this purpose in view that the hinged plates 5 and 6 are provided. Flexible cable portions 15 and 16 are connected with the hinged plates 5 and 6 at the outer edges thereof and are extended through the openings 17 and 18 in the outer sole 2, so that as drawing tension is exerted upon the outer ends of these cable portions 40 the plates will be folded up at the hinged edges thereof, and that this folding of the plates may be accomplished, the cables 15 and 16 have the right and left hand threaded rods 19 and 20 carried on the free ends 45 thereof, a turn buckle portion 21 being mounted on these oppositely threaded ends to be turned to draw in the cables. That the turn buckle portion 21 may be readily turned, openings 22 are provided in the sides 50 thereof for the reception of a nail or other instrument which might be inserted and used as a pry lever in turning the turn buckle 21. This structure is all mounted so that the outer ends of the cables 15 and 55 16, the screw-threaded rods 19 and 20, and the turn buckle portion 21 will be close up against the outer sole 2 at the instep and thus the parts will be protected.

From the foregoing it will be seen that I 60 have provided a structure which gives a cushion inner sole for contact with the plantar surface of the foot together with a pneumatic pad support for the metatarsal arch, and that by varying the quantity of 65 air filled into the inflatable bladder 13

through the valve stem 14, and by manipulation of the turn buckle 21, the height of the supporting pad for the metatarsal arch can be varied.

While I have herein described and specified one particular embodiment of the present invention and have shown only certain parts and certain manners of associating the same, it is to be understood that in practice, I do not limit myself to such specific details but 75 may resort to any practical modifications falling within the scope of the invention as defined in the appended claims.

I claim:

1. An arch supporting shoe including 80 with an inner sole structure against which the foot bears, inflatable means to give elevation and to vary the elevation of the inner sole structure at the instep arch, and means to bodily raise and support the inflatable 85 means.

2. An arch supporting shoe including a middle sole having an inner sole mounted thereon and in part loosely associated therewith, an inflatable bladder mounted upon the middle sole and disposed beneath the inner sole at the instep arch, a valve stem extending to the exterior of the shoe through which air is supplied to the inflatable bladder, a pair of plates hingedly connected together and mounted on the middle sole beneath the inflatable bladder, cables connected with the free edges of said plates and extended through the outer sole of the shoe structure, oppositely screw-threaded rods carried by the ends of said cables, and a turn buckle turned on to said screw-threaded rods. 90

3. An arch supporting shoe including a middle sole having an inner sole mounted thereon and in part loosely associated, an inflatable bladder mounted upon the middle sole and disposed beneath the inner sole at the instep arch, a valve stem extending to the exterior of the shoe through which air is supplied to the inflatable bladder, a pair of plates hingedly connected together and mounted on the middle sole beneath the inflatable bladder, cables connected with the free edges of said plates and extended through the outer sole of the shoe structure, oppositely screw-threaded rods carried by the ends of said cables, a turn buckle turned on to said screw-threaded rods, and cushion means mounted between the middle and inner soles to give a cushion support to the inner sole. 105

4. An arch supporting shoe comprising a middle sole, an inner sole mounted thereon and provided with an aperture formed therein adjacent a point directly above the arch of the shoe, said inner sole tapering upon its lower face adjacent the periphery of said aperture, a lining strip fitting over the top of said inner sole, and a pneumatic 110
